(57) **CLAIM**

The ornamental design for a lid for food container, as shown and described.

DESCRIPTION

FIG. 1 is a front perspective view of a lid for food container of the present invention;

FIG. 2 is a top view thereof;

FIG. 3 is a bottom view thereof;

FIG. 4 is a side view thereof;

FIG. 5 is a cross section view taken along lines 5-5 of FIG. 2;

FIG. 6 is a cross section view taken along lines 6-6 of FIG. 2;

FIG. 7 is a cross section view taken along lines 7-7 of FIG. 2;

FIG. 8 is an environmental perspective view showing the lid for food container coupled to a container;

FIG. 9 is a front perspective view of an alternative embodiment of the lid for food container of the present invention;

FIG. 10 is a top view thereof;

FIG. 11 is a bottom view thereof;

FIG. 12 is a side view thereof;

FIG. 13 is a cross section view taken along lines 13-13 of FIG. 10;

FIG. 14 is a cross section view taken along lines 14-14 of FIG. 10;

FIG. 15 is a cross section view taken along lines 15-15 of FIG. 10; and,

FIG. 16 is an environmental perspective view showing the lid for food container coupled to a container.

In the drawings, the broken line showing portions of a container depicts environment and forms no part of the claim.
